UNITED STATES PATENT OFFICE

2,650,385

BUFFING PAD CUSHION HAVING PASSAGES FOR CIRCULATING COOLING AIR THROUGH THE CUSHION TO THE BUFFING PAD

Frank De Michel, Chicago, Ill.

Application December 12, 1947, Serial No. 791,302

4 Claims. (Cl. 15—230)

1

My invention relates to an improvement in cushions for power driven buffing pads and more specifically to the provision of means for cooling such a pad and cushion.

The destructive qualities of heat incident to buffing operations both on the pad and on the work are well known, and one object of my invention, therefore, is to provide a novel cushion for a buffing pad which reduces the accumulation of frictional heat generated in buffing.

Another object of my invention is to provide a novel means for air cooling a cushion for a buffing pad so that the cushion may be made of sponge rubber which is ideally suited for this purpose other than in resistance to heat.

Other objects and advantages of my invention will appear from the following description and drawings, in which:

Fig. 1 is a top plan view of the cushion overlaid in part with a section of a buffing pad and broken away in part to illustrate other pad details and the structure of the cushion;

Fig. 2 is a vertical sectional view which may be considered as being taken substantially along the line 2—2 of Fig. 1 looking in the direction of the arrows;

Fig. 3 is a horizontal sectional view of a modification of my invention which may be considered as being taken substantially along the line 3—3 of Fig. 4 looking in the direction of the arrows; and

Fig. 4 is a vertical sectional view of this modification which may be considered as being taken substantially along the line 4—4 of Fig. 3 looking in the direction of the arrows.

My invention comprises primarily a hub member 10, a cushion 12, and a nut 14. The hub member 10 is an approximately conical member having a widely flared base which provides a large bearing surface 16 against which the cushion rides. An axial opening 18 is formed in the hub and is adapted to fit loosely around the threaded end 20 of a rotatable power driven shaft 22. The cushion 12 has a flexible laminated base 24 having a plurality of members which may be made of thin flexible steel, phenolic sheets, or other suitable materials. The upper member 26 may have a downwardly dished edge 28 to afford greater support to the edges of the cushion. The laminations may be secured together by rivets 30 or any other suitable means.

A sponge rubber cushion is bonded to the upper surface of the base 24 extending down over the dished edge 28. The upper side of the cushion has a series of sponge rubber elevations 34 formed thereon which serve to support the pad 36 and at the same time define air passages 38 through which air may circulate. As here shown, the ele-

2

vations consist of a separated inner 40 and outer 42 series of wedge shaped ribs extending radially outwardly from the center of the cushion. However, there are many forms which the passages may take. The preferred structure would provide for intercommunication of the passages and some connection with a central hole or cavity 44. To insure simultaneously sufficient air passages and sufficient support, the elevations and passages should be closely spaced. I accomplish this by providing for the two series of ribs separated by the passages 45. Other designs are of course possible. The rubber cushion has the hole 44 passing centrally therethrough, a circular cavity 46 concentric with and opening into the hole 44 formed therein in which the nut 14 is seated to secure the pad to the shaft 22, and slits 48 opening into the hole and extending upward from the cavity to the surface of the pad whereby the nut may be inserted into the cavity.

The nut 14 is similar to that found in the sanding machine art and consists of a tubular member threaded internally to engage the portion 20 of the shaft 22 and adapted to fit between this portion and the axial opening 18 in the hub 10. On its upper end it bears a wide circular flange 52 which locks the pad between it and the surface 16 of the hub.

The buffing pad I prefer to employ with this cushion comprises a sheepskin disk 54 covered with fleece 56 having a drawstring sheath 58 secured to the perimeter thereof and a drawstring 60 therein. The pad has a central aperture 62 formed therein with a stiff reinforcing piece 64 surrounding the aperture to strengthen its walls. The hole 44 and the aperture 62 are arranged to fall into communicating relation when the pad is placed on the cushion.

The circulation of air within and into and out of the cushion pad is accomplished by the buffing operation. When the spinning buffer is pressed against a surface the elevations 34 at the point of contact will be compressed, lessening the total air capacity of the unit. Hence, some air will be forced out through hole 44 and aperture 62. As the buffer rotates the elevations will be successively depressed and released and the air in the successive passages will pulsate in and out. This incessant motion will result in a continuous turbulence which will hasten the movement of the air between various parts of the device and accelerate the interchange of the heated air for cool air at the orifice 62. Upon a change of the pressure on the buffer the unit will breathe in or out and when the buffer is removed from the work cool air will re-enter to replace the initially displaced air.

The modified form of my invention illustrated

in Figs. 3 and 4 resembles closely the basic form. It employs the same hub 70, nut 72 and laminated base 74. It may be used with the same type pad 76 having the orifice 78. The cushion 80 is again formed of a resilient material, such as sponge rubber, and has a central opening 82 with slits 84 extending outwardly therefrom to provide for the insertion of the nut 72.

The main point of difference rests in the air passage structure. On the upper surface 86 of the cushion a plurality of relatively large ports 88 are formed in the rubber cushion which extend vertically through it and radial passages 90 are formed on the underside thereof into which the ports open. The radial passages are interconnected by an annular passage 92. Here again, the configuration of holes and passages may be varied without departing from the spirit of my invention. The objectives to be achieved are adequate support, closely spaced cooling ports and interconnecting means providing a unitary system. Also, it is desirable that the system be open to the exterior. In this form of the invention the annular passage 92 defines an annular recess 94 about the opening 82 whereby the nut flange 96 may be accommodated between the back 74 and the cushion without causing the central port of the surface of the cushion to bulge. The floor of this recess is grooved to provide other radial passages 98, furnishing communication between the annular passage 92 and the opening 82.

The rubber cushion is bonded to the base between the passages 90 and outside the recess 94. It will be noted here that the nut flange may bear directly on the back without the interposition of any cushion material.

The principle of operation of this modification is the same as that of the first form. Variations in pressure during the buffing operation vary the air capacity to produce a breathing of the cushion and the local pressure change within the cushion at constant buffing pressure causes the pulsation of the air, both contributing to the cooling effect as above described.

Having described my invention, what I claim as new and useful and desire to secure by Letters Patent of the United States is:

1. A cushion for a buffering pad adapted to be connected to a rotatable shaft and to have mounted thereon a buffering pad of the type which encloses the face and periphery of the cushion and which has a small central hole formed therein, said cushion being formed of a spongy easily compressible rubber so that it is locally compressible by buffering pressure, said cushion being formed with air passages therein open to the cushion face normally covered by the pad, and said cushion being formed with a central cavity therein with which the small central hole falls into alignment when the pad is mounted on the cushion, said cavity communicating with said passages, whereby local compression of said cushion under buffering pressure as said cushion and pad are rotated causes circulation of air through said passages, cavity and hole to effect cooling of said cushion and pad.

2. A cushion for a buffering pad adapted to be connected to a rotatable shaft and to have a buffering pad of the type which encloses the face and periphery of the cushion and which has a small central hole formed therein mounted thereon, said cushion being formed of a spongy easily compressible rubber so that it is locally compressible by buffering pressure, said cushion being

formed with a plurality of generally radially disposed air passages therein open to the cushion face normally covered by the pad, and said cushion being formed with a central cavity therein with which the small central hole falls into alignment when the pad is mounted on the cushion, said cavity communicating with the inner ends of said passages, whereby local compression of said cushion under buffering pressure as said cushion and pad are rotated causes circulation of air through said passages, cavity and hole to effect cooling of said cushion and pad.

3. A cushion for a buffering pad adapted to be connected to a rotatable shaft and to have a buffering pad of the type which encloses the face and periphery of the cushion and which has a small central hole formed therein mounted thereon, said cushion being formed of a spongy easily compressible rubber so that it is locally compressible by buffering pressure, said cushion being formed with a plurality of generally radially disposed air passages therein open throughout their lengths to the cushion face normally covered by the pad, and said cushion being formed with a central cavity therein with which the small central hole falls into alignment when the pad is mounted on the cushion, said cavity communicating with the inner ends of said passages, whereby local compression of said cushion under buffering pressure as said cushion and pad are rotated causes circulation of air through said passages, cavity and hole to effect cooling of said cushion and pad.

4. A buffering device adapted to be mounted on a rotatable shaft comprising a cushion formed of a thick spongy easily compressible rubber which is deformable and compressible by buffering pressure, a central cavity formed in said cushion and open to the face thereof, a plurality of generally radially extending grooves formed in the face of said cushion and opening into said cavity at their inner ends, and a buffering pad mounted on said cushion to enclose the face and periphery thereof and having a small central hole therein aligned with said cavity, said grooves, cavity and said pad defining a system of air passages which are locally changed volumetrically by local compression of said cushion during the buffering operation to produce a pulsating movement of air in said system and to and from the atmosphere thereby to cool said cushion and pad.
